TAKE-DOWN ATTACHMENT FOR
PRECOOLING FANSAugust R. Carstensen and Harry W. Davis,
Sacramento, Calif., assignors to Crystal Ice
and Cold Storage Company, Sacramento, Calif.

Application September 22, 1939, Serial No. 296,092

8 Claims. (Cl. 62—24)

This invention relates to the precooling of refrigeration cars by means of portable and removable electric fan units such as that shown for instance in Patent No. 2,099,815, granted November 23, 1937, to J. R. Lewis et al., as well as various others, and particularly deals with a means for facilitating the removal of such units from the car after the precooling operation is completed.

10 The principal object of our invention is to provide such a means which not only avoids the necessity of crawling over the load to disengage and remove the fan units from their supported operative position adjacent the ice bunkers of 15 the car, but enables such removal to be effected with a minimum of time and effort, and with a minimum of additional equipment or parts. Also, such equipment as is permanently mounted in the car is relatively small and inexpensive and is not 20 in the way of loading operations.

These objects we accomplish by means of such structure and relative arrangement of parts as will fully appear by a perusal of the following specification and claims.

25 In the drawing similar characters of reference indicate corresponding parts in the several views: Figure 1 is a fragmentary longitudinal sectional outline of a refrigerator car showing a precooling fan unit as mounted in operative position and provided with our improved take-out equipment.

Figure 2 is a similar view showing the fan unit as being taken out.

Figure 3 is an end view of the fan unit, 35 tacked.

Referring now more particularly to the characters of reference on the drawing, the fan unit used with our take-out equipment comprises essentially a cylindrical housing 1 containing the 40 motor driven fan 2 and having at one end a canvas hood 3 adapted to surround the top opening 4 of an ice bunker 5 of the refrigerator car 6 and to be tacked about said opening.

An eye 7 is mounted on and projects upwardly 45 from the housing at a point in its length such that the weight of the unit is substantially balanced. When the fan unit is in operating position, this eye is engaged with an L-shaped hook 8 which depends from and is permanently mounted 50 in the ceiling 9 of the car and facing away from the adjacent ice bunker.

The housing is rigidly mounted on a longitudinally extending relatively wide shoe or runner 10, and this shoe, if desired, may be provided with 55

longitudinally spaced transverse rollers 11 underneath.

A pull cable 12 is connected to the housing at the top, preferably at the eye 7 as shown in Fig. 3, and extends through a ceiling mounted eye 13 disposed relatively close to but ahead of hook 8. This cable initially extends to the door end of the adjacent portion of the load L in the car as shown in Fig. 1.

Another pull cable 14 extends from a similar point in the car to a connection with the adjacent end of the shoe 10, the portion of the cable adjacent the shoe being preferably branched as shown at 15.

The fan unit is mounted in place before the car is loaded, the cable 12 being threaded through eye 13 after the unit is hung, and both cables being then caught and held out of the way of loading operations.

When it is desired to take out the fan unit after 20 precooling is completed, a runway or plank unit 16 (which may be sectional), is laid on the load directly under the fan unit. The cable 13 is then pulled sufficiently to disengage the eye 7 from hook 8, the hood 3 readily pulling loose from the 25 bunker wall, since only light tacking is employed. The fan unit then drops onto and becomes supported by the runway. If this drop is small, the shock is insufficient to cause any damage either to the load or fan unit. If the load is 30 shallow and the drop consequently great, a grip on the cable is retained so that the weight of the unit may be supported by the portion of the cable depending from the eye 13, and the cable is then 35 payed out so as to lower the unit gently onto the runway.

Once the unit is on the runway, the cable 12 is released and the cable 14 is pulled, drawing the unit toward the center of the car where it may be picked up and removed through the 40 door. While the unit is thus moving, the cable 12 runs out of itself from the eye 13, as indicated in Fig. 2.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we 55

claim as new and useful and desire to secure by Letters Patent is:

1. Mounting and withdrawal means for a portable precooling fan unit for use in cooperative association with an end ice bunker of a refrigerator car, said unit comprising a housing; said means comprising an eye on top of the housing, a hook for engagement with the eye mounted on and depending from the ceiling of the car and facing away from the bunker, said hook being positioned so that when the eye is engaged therewith, the unit is in operative position relative to the bunker, a cable engaging member mounted on and depending from the ceiling adjacent the hook but between said hook and the center of the car, a cable secured at one end on the top of the unit and extending thence through the ceiling mounted eye to an initial termination adjacent the center of the car, a shoe rigid with and extending lengthwise of and under the unit and another cable connected to the end of the unit furthest from the bunker and extending to an initial termination adjacent the center of the car.
2. A device as in claim 1, with a runway to support the unit when released from the hook and adapted to be placed on the load in the car and to extend from under the unit when suspended to adjacent the car door end of the load.
3. A device as in claim 1, with a runway to support the unit when released from the hook and adapted to be placed on the load in the car and to extend from under the unit when suspended to adjacent the car door end of the load and rollers on the unit to ride on the runway when the unit is lowered from engagement with the hook.
4. Mounting and withdrawal means for a portable precooling fan unit for use in cooperative association with an end ice bunker of a refrigerator car; said means comprising an eye on top of the unit, a hook for engagement with the eye mounted on and depending from the ceiling of the car and facing away from the bunker, said hook being positioned so that when the eye is engaged therewith, the unit is in operative position relative to the bunker, a cable engaging member mounted on and depending from the ceiling adjacent the hook but between said hook and the center of the car, a cable secured at one end on the top of the unit and extending thence through the ceiling mounted eye to an initial termination adjacent the center of the car and another cable applied to the unit and also extending to an initial termination adjacent the center of the car.
5. Mounting and withdrawal means for a portable precooling fan unit for use in cooperative association with an end ice bunker of a refrigerator car, said unit comprising a housing; said means comprising an eye on top of the housing, a hook for engagement with the eye mounted on and depending from the ceiling of the car and facing away from the bunker, said hook being positioned so that when the eye is engaged therewith, the unit is in operative position relative to the bunker, means operable from adjacent the center of the car for pulling the eye off the hook and a cable applied to the unit to then pull the same toward the center of the car.
6. Mounting and withdrawal means for a portable precooling fan unit for use in cooperative association with an end ice bunker of a refrigerator car; said means comprising disengageable cooperating elements on the unit and the ceiling of the car to releasably support the unit suspended from the ceiling in cooperative relation to the bunker, means operable from adjacent the center of the car to disengage the cooperating elements and allow the unit to drop and means applied to the unit to then pull the same toward the center of the car.
7. Mounting and withdrawal means for a portable precooling fan unit for use in cooperative association with an end ice bunker of a refrigerator car; said means comprising disengageable cooperating elements on the unit and the ceiling of the car to releasably support the unit suspended from the ceiling in cooperative relation to the bunker, means operable from adjacent the center of the car to disengage the cooperating elements and to then control the lowering movement of the released unit and other means also operable from adjacent the center of the car to then pull the unit toward said center.
8. A structure as in claim 6, with a runway adapted to be placed on the load in the car and to extend from adjacent the car door end of the load to a termination under the unit when the latter is suspended to receive said unit when released.

AUGUST R. CARSTENSEN.

HARRY W. DAVIS.
